United States Patent Office

Des. 227,596
Patented July 3, 1973

227,596

TONE ARM

David C. Bailey, Westfield, N.J., assignor to
General Electric Company

Filed June 24, 1971, Ser. No. 156,593

Term of patent 14 years

Int. Cl. D14—01

U.S. Cl. D56—4 R

FIG.1

FIG.2

FIG.3

FIG.4

FIG. 1 is a perspective view of a tone arm showing my new design;

FIG. 2 is a top plan view;

FIG. 3 is a left side view; and

FIG. 4 is a right side view thereof.

I claim:

The ornamental design for a tone arm, as shown.
